UNITED STATES PATENT OFFICE.

HARRY E. MYERS, OF CLEVELAND, OHIO, ASSIGNOR TO MYERS, OSBORN & CO., OF SAME PLACE.

OIL-STOVE.

SPECIFICATION forming part of Letters Patent No. 319,013, dated June 2, 1883.

Application filed December 24, 1883. (No model.)

To all whom it may concern:

Be it known that I, HARRY E. MYERS, a citizen of the United States, residing at Cleveland, in the county of Cuyahoga and State of Ohio, have invented a new and useful Improvement in Oil-Stoves; and I do hereby declare that the following is a full, clear, concise, and exact description of the invention, and of the manner of constructing and using it, so as to enable any person skilled in the art to which it appertains to construct and use the same, reference being had to the accompanying drawings, forming a part of this specification, the principle of the invention being herein explained and the best mode in which I have contemplated applying that principle, so as to distinguish it from other inventions.

Heretofore in oil-stoves chimneys that slide over the wick-cone independently of and separately from a sliding lamp, as shown in United States Patent No. 240,589, issued April 26, 1881, to L. C. Heckman, have been provided with no means of holding them firm in said position aside from their close lateral fitting to said cone, so that they are thereby subject to motion, rattling, and possible displacement as the stove-drum is thrown back.

To remedy this objectionable feature is the principal object of the present invention, which is accomplished by providing the chimney with bottom flanges fitting under bars located, respectively, on opposite sides of the wick-cone, as herein described and claimed. This adaptation of parts differs from a construction which moves a complete lamp in and out of the drum, or under a drum of a stove or heater by flanges and slide ways, as shown in United States Patent No. No. 223,977, issued to M. C. Armour, February 3, 1880, and United States Patent No. 195,255, issued to M. Bradley, September 18, 1877. There are manifest advantages of having the chimney removable independently of the lamp, as in the aforesaid cited invention of Heckman; but in the said Heckman's chimney there is no provision of flanges to hold the

chimney firmly over the wick-cone; nor is the cone-plate of his patent provided with any device to receive and hold flanges formed on the bottom of a chimney. In the present invention said flanges and a device to receive and hold them are provided for, thus answering the ends already indicated.

In the drawings, Figure 1 is a vertical cross-sectional view of the invention. Fig. 2 is a top perspective from the rear, showing the guides and stop in one and the chimney cut away.

In carrying out my invention I form substantial flanges *a* on the bottom edges of the chimney *A*, adapted to fit in the grooves *b*, formed on the under faces of bars *B*. Bars *B* are located along the sides of the wick-cone on the cone-plate *C*, said bars being also provided with bolt-holes *c*, by which they are attachable to the cone-plate. The rear ends of a pair of these said bars are cast solid with the stop *D*, said stop arresting the inward movement of the chimney, and also aiding in holding the chimney in position. Bars *B* are unconnected with each other at their forward ends. The chimney has its back portion cut away in such a manner that it may be slid over the wick-cone.

What I therefore claim is—

In an oil-stove, the combination, with a wick-cone and a sliding chimney, *A*, formed with the outwardly-projecting bottom flanges, *a*, of the detachable bars *B*, located on the upper side of the cone-plate *C* and contiguous to its base, said bars being connected together at their rear end by stop *D*, cast solid with them, and said bars also provided, respectively, with the longitudinal groove *b*, formed on their under edge next to the wick-cone and the cone-plate, substantially as set forth.

In testimony that I claim the foregoing to be my invention I have hereunto set my hand this 19th day of December, 1883.

HARRY E. MYERS.
